UNITED STATES PATENT OFFICE.

EUGENE L. RAGONNET, OF LANGHORNE, PENNSYLVANIA.

HYDRO-PNEUMATIC LOCOMOTIVE REVERSING-GEAR.

1,147,436.

Specification of Letters Patent. Patented July 20, 1915.

Application filed March 19, 1915. Serial No. 15,418.

To all whom it may concern:

Be it known that I, EUGENE L. RAGONNET, a citizen of the Republic of France, residing at Langhorne, county of Bucks, and 5 State of Pennsylvania, have invented certain new and useful Improvements in Hydropneumatic Locomotive Reversing-Gear, fully described and represented in the following specification and the accompanying 10 drawings, forming a part of the same.

The present invention relates to a locomotive valve reverse gear in which a cylinder is provided with a piston connected directly to the reversing-arm of the valve-gear, 15 and the piston is actuated by liquid under pressure, the movements of which are controlled by a valve, and the valve operated by a hand-lever in the locomotive cab.

The store of liquid is contained in two 20 reservoirs which have connections to opposite ends of the cylinder, and the valve is supplied with compressed air and has ports for directing such air alternately into the opposite reservoirs, and also ports which 25 simultaneously direct the passage of the fluid from one reservoir to one end of the cylinder and from the opposite end of the cylinder to the other reservoir.

When the valve is in its mid position it 30 closes all the ports and cuts off all escape of liquid from the cylinder, thus preventing any movement of the piston and locking the reversing-arm in whatever position it may have been moved by the piston.

As the hand-lever and the valve would 35 be moved to the mid position for thus locking the piston, their position would not afford any indication of the adjustment of the reversing-arm, and a movable index is 40 therefore preferably mounted adjacent to the hand-lever in the cab and connected to the reversing-arm so as to indicate the position of such arm.

In order that my piston-rod may be connected directly to the reversing-arm of the 45 valve-gear, I form the reversing-cylinder entirely separate from the reservoirs, and thus permit the reservoirs to be located at any convenient point upon the locomotive 50 apart from the reversing-cylinder. This separation of the parts gives great independence of arrangement in applying my

invention to locomotives of various constructions, and permits the cylinders and their reversing-valve to be located at one 55 point upon the locomotive, and the cylinder with its piston-rod to be located at another point next the reversing-arm, and the hand-lever to be located in the cab, with connection to the reversing-valve upon the reservoirs. 60

The invention consists in the combinations hereinafter described and set forth, and which will be understood by reference to the annexed drawing, in which— 65

Figure 1 is a diagrammatic view of the cylinder with its piston connected to the reversing-arm and the reservoirs with a valve and hand-lever mounted thereon, the parts being in section at the center line where 70 hatched; Fig. 2 is a section of the valve and part of the reservoirs with the valve moved to open the ports; Fig. 3 is a vertical section of the valve-casing on the middle line of Fig. 2, with the various valve-connections, the valve itself not being in section; Fig. 4 is an elevation of a locomotive with a diagrammatic representation of the reversing apparatus; and Fig. 5 is a diagrammatic representation of the apparatus in an 75 alternative form, with the reservoirs and valve fixed upon the side of the boiler, and only the hand-lever mounted in the cab. 80

In Fig. 4, A designates the body of the locomotive boiler, B the fire-box, C the cab, 85 and a the hand-lever for actuating the valve reversing gear.

The valve-casing and the reservoirs may be formed integral, as shown in Fig. 1 and as represented in the cab in Fig. 4, with the 90 valve-casing c formed integral with the reservoirs b, b', and the hand-lever attached to the spindle c' of the valve.

In Fig. 4, the reversing-cylinder D is shown pivoted upon the fulcrum E which is 95 mounted upon the engine-frame F, and the piston-rod H' jointed directly to a reversing-arm G which operates upon the reversing-link G' of the engine in any suitable manner to reverse the valves of the locomotive-cylinders. 100

The pivoting of the cylinder at its rear end upon the fulcrum permits the direct connection of the piston-rod to the revers-

ing-arm G, which in its movements necessarily causes a slight oscillation of the cylinder upon the fulcrum.

The pipes connecting the cylinder with the valve-casing are so small that they bend readily under such oscillating movement, and require no movable joints or couplings.

Referring to Fig. 1, the cylinder and valve-casing are shown connected together, but crowded close to one another, for want of room upon the drawing, in a relation which would not occur in practice.

In practice, the reservoirs with the valve and hand-lever may be located in the cab, as shown in Fig. 4, and the valve-casing connected with the cylinder by suitable pipes, but the use of long pipes between the valve-casing and the cylinder may be avoided by locating only the hand-lever in the cab and mounting the reservoirs and associated valve-casing on the boiler close to the cylinder, as shown diagrammatically in Fig. 5.

In Fig. 1, the valve-casing e is provided at opposite sides with ports e, e', which connect by pipes D' and D'' with the opposite ends of the cylinder D.

The casing is provided with a nozzle e² connected with a supply of air under pressure. The casing e is provided with ports f, f', which open directly into the upper parts of the reservoirs b, b', and with ports g, g', which connect with the bottoms of the reservoirs b, b', through passages h, h'.

The valve-casing is made with a conical seat as shown in Fig. 3, and the valve j is formed of a conical frustum with the spindle h extended from its smaller end and carrying the hand-lever l and the index-hand m.

The casing is provided with a cover or removable head c', and a chamber c² is provided in such head to receive a spring p which presses against the larger end of the valve and holds it firmly upon its conical seat.

The valve, as shown in Figs. 1 and 2, has pockets in its periphery, the pocket n being in constant connection with the air-inlet e², and with passages n' which are adapted to connect alternately with the ports f, f'. The opposite edges of the valve are provided with pockets o, o', adapted alternately to connect the passages h, h' with the ports g, g'.

The valve-casing is shown provided with a segment q having a notch q' at the middle of its length, to engage a latch r upon the hand-lever a in its mid position, and an index-arch s is attached to the segment by studs s', shown in Figs. 1 and 3, to indicate the position of the index-hand m which is connected with the reversing-arm by connections t', and crank t on rock-shaft G'.

The valve and hand-lever are shown in

their mid-position in Fig. 1 with the passages n' closed against the wall of the casing, and the ports e, e' and the ports g, g', also closed, so that there is no movement of liquid in the reservoirs or in the cylinder D.

The setting of the hand-lever in such mid-position therefore prevents any movement of the piston, as the liquid on either side of the same can only escape through the port e or e', which in such position of the valve is wholly closed.

The valve is shown in Fig. 2 rocked as by moving the hand-lever to the right, thus connecting one of the passages n' with the port f', and forcing the liquid in the reservoir b' upward through the port g into the pocket o' and thence through the port e' and pipe D² to the forward end of the cylinder.

The ports in the valve-casing are made relatively small so as not to produce any sudden movement of the piston h when the valve is moved, but to actuate the valve reversing gear as rapidly as is safe or desirable.

When the hand-lever is held in the position of Fig. 2 for a short time, the piston is moved to the inner end of the cylinder D as shown in Fig. 1, thus moving the reversing lever G in one direction, and when the hand-lever is moved and held in the opposite direction it moves the reversing-lever to the opposite extreme indicated by the dotted lines G' in Fig. 1. The middle position of the reversing-lever is indicated by the dotted lines G² in Fig. 1.

The movement of the index-hand m corresponds exactly with these movements of the reversing-lever, such index-hand being in the middle of its arch s when the reversing-lever is in its middle position, and moving forward and backward when the reversing-lever is moved forward or backward, thus enabling the engineer to determine the extent to which the reversing-lever has been moved by the operation of the valve, and thus guiding him in checking such reverse movement and shifting the hand-lever to its mid position, in which position the reversing-lever is locked firmly by the closing of all the cylinder ports.

When the liquid in either of the reservoirs is forced into the cylinder D and moves the piston, a corresponding amount of liquid is forced by the piston into the opposite reservoir, which is vented at such time by the pocket u in the edge of the valve, which connects the port g or g' with an exhaust-port u', which port opens directly to the atmosphere, as shown in Fig. 3.

In Fig. 5, a segment Q is shown secured to the boiler by a foot R having the bearing R' for the hand-lever a', and the reservoirs b, b' are shown mounted upon the side of the boiler not far from the cylinder D, so that

the pipes D' and D^2 may be carried beneath the casing or jacket of the boiler close to the cylinder, thus avoiding exposure to accidental injury.

5 The valve-spindle k in this case is provided with an arm k' linked to the hand-lever a' by a rod k^2 , and the valve is thus operated with the same facility as if it were in the cab. The index-hand m is shown in Fig. 5 with part of the link t' which connects it with the reversing-arm; such link being broken by the diagrammatic character of the drawing.

10 In this invention, the reversing-cylinder D is entirely distinct or separate from the liquid-controlling devices which produce the movements of its piston, and it may therefore be arranged in a horizontal position or vertically above or below the valve reversing 20 rock-shaft.

15 This affords great facility in applying the invention to existing engines of various types or constructions, as it permits the reversing-cylinder to be attached to the boiler, 25 the frame, or any other part of the engine which furnishes the most convenient location for the fulcrum E . The separation of the reversing-cylinder from the larger part of the apparatus (which comprises the reser- 30 voirs and hand-moved valve) enables such larger part to be placed in some convenient location other than that where the cylinder must necessarily be set, to take directly hold of the reversing-lever.

35 My invention permits great simplicity of construction, as it involves the use of very few parts, and the construction also affords the following advantages. The pivoting of the valve reversing-cylinder D to a fixed 40 fulcrum permits the piston-rod of the cylinder to be jointed directly to the reversing-arm of the rock-shaft, the joint of which moves through an arc of a circle, when reversing the valves, and causes a slight oscillation of the cylinder. This construction avoids the necessity of using a connecting 45 rod of any kind between the piston and the reversing-arm, and avoids the lost motion which results from wear in such connections.

50 The use of a conical distributing valve, such as is shown in Fig. 5, maintains a tight joint between the valve and casing, so that wear does not cause leakage, the construction permitting the parts to be ground accurately 55 when manufactured, and to be maintained in perfect condition by subsequent grinding, if required.

The spring c^2 which presses upon the larger end of the valve-body holds the valve 60 upon its seat with an elastic pressure, and as none of the passages or pockets in the valve-body extend to its smaller end, there is no tendency for fluid to escape from the casing at the smaller end of the valve-body, and no

stuffing-box is therefore required around the 65 spindle k .

This reduces the cost of construction and permits the hand-lever a to be attached to the spindle close to the bearing, as indicated in Fig. 5, where a nut holds such hand-lever 70 securely upon the spindle; and it also permits the index-hand m to be fitted movably upon an extension k' of the spindle where it is held in place by a cotter m' .

The co-axial arrangement of the hand-lever and the index-hand permits the support of an arch s upon the segment q by means of the studs s' , the concentric arrangement of the segment q and the index-arch s being clearly shown in Fig. 1.

75 While it is not necessary to the invention that this particular form of valve be used, it is evident that it possesses many advantages.

80 Having thus set forth the nature of the invention what is claimed herein is:

1. In a locomotive valve reverse gear, the combination, with a fulcrum upon the engine adjacent to the valve reversing-arm, of a cylinder pivoted to oscillate upon such fulcrum and having its piston connected to such reversing-arm, and means for supplying fluid reversely to the said cylinder.

2. In a locomotive valve reverse gear, the combination, with a fulcrum upon the engine adjacent to the valve reversing-arm, of a cylinder pivoted to oscillate upon such fulcrum with its piston connected to the valve reversing-arm, fluid connections to opposite ends of the cylinder and a hand-lever in the 100 cab for controlling the flow of fluid in such connections.

3. In a locomotive valve reverse gear, the combination, with a fulcrum upon the engine adjacent to the valve reversing-arm, of a cylinder pivoted to oscillate upon such fulcrum with its piston connected to the valve reversing-arm, two liquid-reservoirs with liquid connections to the opposite ends of the said cylinder, and a hand-lever in the 105 cab with connections for supplying fluid under pressure alternatively to the said reservoirs.

4. In a locomotive valve reverse gear, the combination, with a fulcrum upon the engine adjacent to the valve reversing-arm, of a cylinder pivoted to oscillate upon such fulcrum with its piston connected to the valve reversing-arm, two liquid-reservoirs with liquid connections to the opposite ends of the said cylinder, a conical valve mounted 115 in the cab with hand-lever to oscillate the same, and ports controlled by the said valve for supplying air under pressure alternately to the two reservoirs.

5. In a locomotive valve reverse gear, the combination, with a fulcrum upon the engine adjacent to the valve reversing-arm, of a cylinder pivoted to oscillate upon such ful-

- crum with its piston connected to the valve reversing-arm, two liquid-reservoirs with liquid-connections to the opposite ends of the said cylinder, a conical valve mounted in 5 the cab with pipe supplying compressed air thereto, and valve passages for directing the air alternately into the two reservoirs.
6. In a locomotive valve reverse gear, the combination, with a fulcrum upon the engine 10 adjacent to the valve reversing-arm, of a cylinder pivoted to oscillate upon such fulcrum with its piston connected to the valve reversing-arm, two liquid reservoirs with liquid connections to the opposite ends of 15 the said cylinder, a valve with hand-lever to actuate the same, a connection supplying compressed air to the valve, ports controlled by the said valve for supplying the air under pressure alternately to the two reservoirs, and liquid passages in the valve adapted 20 when adjusted in opposite positions to direct the liquid from the reservoirs into the opposite ends of the cylinder, and when placed in the intermediate position, to prevent any flow of liquid from the cylinder, and thereby lock its piston in the adjusted 25 position.
7. In a locomotive valve reverse gear, the combination, with a fulcrum upon the engine 30 adjacent to the valve reversing arm, of a cylinder pivoted to oscillate upon such fulcrum with its piston connected to the valve reversing-arm, two liquid reservoirs with liquid connections to the opposite ends of 35 the said cylinder, a conical valve mounted in the cab with pipe supplying compressed air thereto, valve passages for directing the air alternately into the two reservoirs, liquid 40 passages in the valve-casing connecting the reservoirs respectively with the opposite ends of the cylinder, pockets in the valve adapted, when adjusted in opposite positions, to direct the liquid into the opposite ends of the cylinder, and when placed in the 45 intermediate position to prevent any flow of liquid from the cylinder, and thereby lock its piston in its adjusted position.
8. In a locomotive valve reverse gear, the combination, with a cylinder having piston 50 connected directly to the valve reversing-arm, of two liquid-reservoirs independent of the cylinder, and having liquid connections to the opposite ends of the said cylinder, a valve and a hand-lever to actuate the same 55 located in the cab, the valve having ports to direct the liquid into the opposite ends of the cylinder at pleasure and adapted when placed in the intermediate position to prevent any flow of liquid from the cylinder 60 and thereby lock its piston and the reversing-arm in the adjusted position, and an index associated with and movable independently of the valve and having connection to the reversing-arm and operating to

show the adjusted position of the said arm.

9. In a locomotive valve reversing gear, the combination, with a hand-lever in the cab, of two liquid reservoirs with a valve actuated by the hand-lever to discharge the liquid at pleasure from either of the reservoirs and a valve reversing cylinder and piston independent of the reservoirs, to permit their location at any convenient point upon the locomotive, the cylinder being pivoted upon a fulcrum to permit the oscillation of the cylinder with its piston-rod connected directly to the valve reversing-arm, the cylinder-ends being connected respectively with the two reservoirs so that its piston is reciprocated in accordance with the movements of the hand-lever.

10. In a locomotive valve reversing gear, the combination, with a hand-lever in the cab, a valve reversing-cylinder pivoted upon a fulcrum to permit its oscillations, and a piston having a piston-rod connected directly to the valve reversing-arm, of two liquid-reservoirs connected respectively to the opposite ends of the cylinder, and a 85 conical valve and casing with a spring to press the valve elastically to its seat, the valve having pockets and passages terminating upon its periphery only and having no liquid pressure upon its smaller end, the 90 valve-spindle projected from such smaller end, whereby the spindle requires no packing, and an operating lever attached to such spindle.

11. In a locomotive valve reversing gear, the combination, with a valve reversing-cylinder pivoted upon a fulcrum to permit its oscillations, and a piston having a piston-rod connected directly to the valve reversing-arm, of two liquid reservoirs connected 105 respectively to the opposite ends of the cylinder, and a conical valve and casing with spindle projected from the smaller end of the valve and having an operating lever attached thereto, an extension upon such spindle having an index-hand fitting movably thereto, and a connection from the valve reversing-arm to the said index-hand to indicate the position of such arm and valve-gear.

12. In a locomotive valve reversing gear, 115 the combination, with a valve reversing-cylinder pivoted upon a fulcrum to permit its oscillations, and a piston having a piston-rod connected directly to the valve reversing-arm, of two liquid-reservoirs connected 120 respectively to the opposite ends of the cylinder and a conical valve and casing with spindle projected from the smaller end of the valve and having an operating lever attached thereto, a segment mounted upon the 125 valve-casing for locking the operating lever, an index-arch connected to the side of such segment with space between the two for the

movement of the operating lever, an extension upon the spindle having an index-hand fitted movably thereto and extended to the said arch, and a connection from the 5 valve reversing-arm to the said index-hand to indicate the position of such arm and valve-gear.

In testimony whereof I have hereunto set my hand in the presence of two subscribing witnesses.

EUGENE L. RAGONNET.
